CLAIM

The ornamental design for a plant container, as shown and described.

DESCRIPTION

FIG. 1 is a perspective view of a plant container showing our new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a bottom plan view thereof; and,

FIG. 7 is an exploded left side elevation view thereof.

The broken lines depict environmental subject matter only and form no part of the claimed design.
